PUMPING APPARATUS

Charles M. O'Leary, Los Angeles, Calif.

Application March 18, 1938, Serial No. 196,752

7 Claims. (Cl. 74—589)

This invention relates to pumping apparatus.

The present invention is particularly concerned with well pumping apparatus used in connection with the pumping of oil from deep wells, and is of the general type shown in my co-pending application entitled Oil well pump and counterbalance, filed concurrently herewith. In this type of pumping apparatus a power drive is provided for actuating a walking beam, at the free end of which well pump rods are connected and by which said pump rods are reciprocated. The present invention is concerned with a fluid counterbalancing cushioning and compensating means whereby fluid circulating through the apparatus in a continuous flow will be maintained at a constant pressure incident to the actuation of the apparatus, and will thus insure that the fluid pressure conditions within the apparatus are maintained constant at all times for the purposes hereinbefore explained.

The present invention contemplates the provision of a walking beam provided with power means to produce its oscillation, and which beam reciprocates a well pumping mechanism, said beam being fitted with a cushioning unit of the fluid type through which a constant flow of incompressible fluid is maintained at all times.

The invention is illustrated by way of example in the accompanying drawings in which:

Figure 1 is a view in side elevation showing the application of the present invention to a well pumping mechanism.

Figure 2 is an enlarged view in vertical section and elevation showing a fluid cushioning unit.

Figure 3 is a top view of the compression tank. Referring more particularly to the drawings 10 indicates a Samson post upon which a walking beam 11 is mounted. A pivot pin 12 attaches the walking beam to the Samson post and permits free oscillating movement of the walking beam. At one end of the walking beam is a horse head 13 to receive the reins 14 of a polish rod 15. It will be understood that the polish rod extends downwardly into a well casing 16 and operates the plunger 17 of a pump. At a point in the length of the walking beam a pivot pin 18 is mounted to receive the end of a pitman rod 19. The pitman rod is connected by a wrist pin 20 with a crank 21 which is mounted upon a shaft 22 driven by a pulley 23. It is understood that the pulley receives its power from a suitable source of power supply not shown, and that if desired other forms of driving mechanism may be used. The drawings in

the present instance merely show a simple form of power unit and it is to be understood that while the walking beam is here shown as being of the simple lever type, power might be applied to the beam at other points, such for example as at a point between the horse head and the Samson post.

Disposed at a point between the horse head and the Samson post is a pivot 24 to which the upper end of a piston rod 25 is connected. This 10 rod extends downwardly to operatively connect the cushioning unit 26 with the walking beam. By reference to Fig. 2 it will be seen that the rod 25 extends downwardly through a guide spider 26'. This spider as shown in Fig. 3 is 16 formed with a plurality of guide arms 27 between which an air circulating space 28 occurs. The spider is mounted over the upper end of a compression cylinder 29 and guides the piston rod 25 as it reciprocates within the cylinder 29 20 and moves its piston 30. The cylinder 29 is mounted within a tank 31. The head 32 of the tank receives a flanged shoulder 33 of the cylinder 29 through which cap screws 34 pass and by which the cylinder 29 is held in position to 25 seal the tank 31 and to form a compression space 35 therein and around the cylinder 29. The lower end of the cylinder 29 is provided with a head 36 having an opening therethrough to which is attached a pipe 37. The pipe 37 extends downwardly and communicates with a main control valve 38, the opposite side of which valve is provided with a pipe 39 connected with a T 40. The T 40 connects with pipes 41 which in turn establish communication with the tank 31 through its 35 bottom head 42. The valve 38 therefor can be used to regulate or interrupt flow of fluid below the piston of the cylinder 29 hereinafter designated as the balancing cylinder and for purposes to be hereinafter set forth. A draw-off pipe 43 40 extends through the wall of the tank 31 and establishes communication with the lower end of the balancing cylinder. This pipe is connected with a four-way coupling 44. The lower leg of this coupling is connected with a bleeder valve 45. The upper leg of the coupling connects with a pipe 46 which carries a check valve 47 connected in turn through a pipe 48 with the tank 31. The remaining leg of the member 44 is provided with a check valve 49. When desired, for 50 purposes hereinafter set forth, the check valve 49 may be utilized to permit a flow of air from the atmosphere to intermittently enter cylinder 29 below piston 30 by way of fitting 44 and pipe 43. This phase of operation is necessary at in- 55

5 intervals for the purpose of establishing a pre-determined pressure of air in the tank 31, and may be accomplished by closing valve 38, thereby causing the non-compressible liquid contained in cylinder 29 below piston 30 to be forced into tank 31 upon the first downward stroke of piston 30, by way of pipes 43 and 46 and through one way check 47 and into tank 31. Thereafter, however, upon further reciprocation of the piston 30 within cylinder 29 air will be caused to displace piston 30 during its up-stroke by entering through check 49, at atmospheric pressure, and into cylinder 29 by way of fitting 44 and pipe 43, to be displaced by piston 30, upon its following downward stroke, into tank 31 by way of pipe 43, fitting 44, pipe 46, and through check 47 into tank 31. Thereby utilizing cylinder 29 and piston 30, together with their associated parts, as a means for developing a pre-determined pressure of air in tank 31.

10 The valves 38 and 45 may be operated manually for the purpose of spacing or holding the walking beam 11 in any desired position, or may be used for the purpose of isolating the pressure in tank 31 from the cylinder 29 below piston 30, by closing valve 38, check 47 permitting flow into tank 31 only, and/or upon opening valve 45 while valve 38 is closed the cylinder 29 below piston 30 may be vented to the atmosphere thereby rendering the piston 30 neutral in order that the crank 21 together with its attached parts may be freely turned to any position. Mounted in the upper end of the tank 31 is a pipe 50. This pipe communicates with the compression space 35 of the tank and to the top of a pressure regulating valve 51. The regulating valve 51 is provided with a suitable pressure diaphragm 52 which acts against a valve rod 53 slidably mounted in a frame 54. A valve element 55 is operated by the rod 53 and when the liquid under pressure within the tank 31 becomes less than a predetermined value the valve element 55 will move on to its seat 56 to become closed. This action will be aided by spring 57 which is carried in the frame 54 and normally acts against collars 58 and 58' to hold the valve 55 on its seat. The valve member 55 is mounted within a valve housing 59 to one side of which is attached a pipe 60 and to the opposite side of which is attached a draw-off pipe 61. The pipe 60 is connected with a T fitting 62, one side of which is attached to a pipe 63 and the other side to a pipe 64. The pipe 63 leads to a gear pump 65. This pump is of conventional design having a housing 66 and pumping gears 67 and 68. The gears are driven through suitable continuously operating driving mechanism. The gear housing 66 is fitted with a pipe 69 leading to the bottom of a storage tank 70 into which sufficient liquid has been placed for operating purposes. The pipe 64 is connected with a check valve 71 through which fluid may flow to a pipe 72 connected directly with the compression space 35 in the tank 31.

15 In the operation of the invention as here shown the valve 38 has been opened to permit the rate of displacement of the incompressible fluid which has been placed within the compression space 73 of the balancing cylinder 29 and in compression space 35 of tank 31. The unit 26 is mounted upon trunnions 74 carried in bearings 75 mounted on supporting elements 76 and the piston rod 25 has been pivotally connected to the walking beam 11 by means of

20 the pivot 24. As the walking beam 11 is oscillated by the driving action of the crank 21 and the pitman rod 19 the piston rod 25 will be reciprocated. On its down stroke it will act against the quantity of incompressible fluid within the compression space 73 to cause it to pass into the tank 31 through the pipe 31 and valve 38 and fitting 40 and pipes 41. This fluid will be displaced from the balancing cylinder 29 and will tend to compress the entrapped volume of air within the tank. The air being a compressible fluid will act to cushion the stroke and when permitted to expand will tend to move the piston 30 upwardly and will aid in lifting the walking beam. The pressure condition desired 15 has been previously determined and the relative volumes of incompressible and compressible fluids have been determined. A constant pressure may be established within the tank 35 by regulation of a nut 77 which adjusts the collar 58 upon the valve stem 53. Thus when the pressure within the compression space 35 of the tank 31 drops below a predetermined minimum the relief of pressure from against the diaphragm 52 will cause the valve stem 53 and its valve 55 to be drawn-upwardly so that the valve 55 seats to prevent the passage of fluid through the pipes 60 and 61 to the tank 70. This will cause the gear pump 65 to draw oil constantly from the tank 70 and direct it through the check valve 71 and the pipe 72 to the compression space 35 of the tank 31. When sufficient oil has been pumped into the tank 31 through the pipe 72 to increase the pressure in the tank to the pressure to which the valve 51 has been adjustably set by the nut 77 the valve 55 will be moved to an opened position and the pipes 60 and 61 will be in communication to atmospheric pressure in storage tank 70. This will cause the flow of oil to be diverted from the pressure pipe 72 to the relief pipes 60 and 61. Thus closing the check valve to maintain the established pressure within the tank 31. It will then be seen that the oil which is constantly pumped through the pump 65 will be diverted back into the tank 70 until such time as the pressure in the tank 31 appreciably lowers and then the valve 55 will reclose to cause the oil to be forced into the tank 31 again. Thus it will be seen that the counterbalancing and cushioning pressure established by the constantly maintained quantity of oil under a constantly controlled pressure insures that as the walking beam and the piston 30 swing downwardly the movement will be resisted by the pressure fluid under piston 30 within the compression chamber 55 73 of the balancing cylinder 29 as developed by the compression of the air within the chamber 35 of the tank 31. It will further be evident that upon the up stroke the expansive action of the air within the compression space 35 will act to aid in lifting the piston 30 and the load which has been imposed upon the walking beam and its power unit. If it is desirable to provide a drain pipe which connects the cushion cylinder 31 with the tank 70 suitable means may be provided so that when an excess of liquid accumulates in the cushion cylinder this liquid may drain back into the tank.

While I have shown the preferred form of my invention, as known to me, it will be understood that various changes might be made in the combination, construction, and arrangement of parts, by those skilled in the art, without departing from the spirit of the invention as claimed.

Having thus described my invention, what I claim and desire to secure by Letters Patent is:

1. In a pumping apparatus for oil wells and the like, of the type including a power actuated walking beam, cushioning and counterbalancing means including a balancing cylinder, a piston therein, a piston rod therefor, the upper end of said piston rod being pivotally connected to the walking beam, a cushion cylinder in free communication with the lower end of the balancing cylinder, means for by-passing an incompressible fluid from the compression chamber of the balancing cylinder to the cushion cylinder, a storage supply of incompressible fluid, means for continuously circulating said incompressible fluid to the balancing cylinder said cushioning cylinder being partially filled with a compressible fluid, and means responsive to variation in pressure of the expandable fluid to interrupt the flow of incompressible fluid from the storage supply to the cushioning cylinder.

2. In a pumping apparatus for oil wells and the like, of the type including a power actuated walking beam, cushioning and counterbalancing means including a balancing cylinder, a piston therein, a piston rod therefor, the upper end of said piston rod being pivotally connected to the walking beam, a cushion cylinder in free communication with the lower end of the balancing cylinder, means for by-passing an incompressible fluid from the compression chamber of the balancing cylinder to the cushion cylinder, a storage supply of incompressible fluid, means for continuously circulating said incompressible fluid to the balancing cylinder, said cushioning cylinder being partially filled with a compressible fluid, means responsive to variation in pressure of the expandable fluid to interrupt the flow of incompressible fluid from the storage supply to the cushioning cylinder.

3. In a well pumping apparatus of the type including a power driven walking beam, a cushioning unit interposed between a fixed base and said beam, said unit comprising a cushioning tank pivoted to the fixed base, a balancing cylinder within said tank open to the atmosphere at its upper end, a piston reciprocating within said balancing cylinder, a piston rod connected therewith and extending outwardly of the open end of the balancing cylinder, the upper end of the rod being connected to the walking beam, a conduit establishing free communication between the bottom of the cushioning tank and the balancing cylinder, the compression space in the balancing cylinder and the space within the bottom of the cushioning tank being filled with an incompressible fluid, while the space within the cushioning tank above the incompressible fluid is filled with a compressible fluid, a storage tank for incompressible fluid, pump means continuously withdrawing incompressible fluid from the storage tank and feeding the same to said cushioning tank, and means responsive to variation in the pressure of the compressible fluid for diverting the flow of incompressible fluid from the cushioning tank and by-passing such fluid to the storage tank when a predetermined pressure has been reached.

4. In a pumping apparatus of the type includ-

ing a power actuated vertically oscillating walking beam, cushioning and counterbalance means comprising a tank pivoted at its lower end to a fixed base, a balancing cylinder associated with said tank and movable therewith, a piston within the balancing cylinder, a piston rod carried by the piston and extending outwardly of the upper open end of the cylinder and pivotally connected to the walking beam, a conduit establishing free communication between the lower end of the balancing cylinder and the lower end of the tank, the space within the balancing cylinder below the piston and the lower portion of the tank being filled with an incompressible fluid, the upper space within the tank containing the compressible fluid, oil storage means, a pump independently and continuously operating to deliver oil from the storage means to the tank whereby to maintain a predetermined quantity of oil within the tank and sustain a predetermined fluid pressure within the tank, a by-pass pipe through which oil from the pump may flow to the storage means, a valve therein, and means for operating the same responsive to variation in the pressure of the compressible fluid within the tank whereby when a maximum fluid pressure has been reached within the tank the valve will divert the oil from the pump to the storage means.

5. In a pumping apparatus of the type including a power actuated vertically oscillating walking beam, cushioning and counterbalance means comprising a tank pivoted at its lower end to a fixed base, a balancing cylinder associated with said tank and movable therewith, a piston within the balancing cylinder, a piston rod carried by the piston and extending outwardly of the upper open end of the cylinder and pivotally connected to the walking beam, a conduit establishing free communication between the lower end of the balancing cylinder and the lower end of the tank, the space within the balancing cylinder below the piston and the lower portion of the tank being filled with an incompressible fluid, the upper space within the tank containing the compressible fluid, oil storage means, a pump independently and continuously operating to deliver oil from the storage means to the tank whereby to maintain a predetermined fluid pressure within the tank, a by-pass pipe through which oil from the pump may flow to the storage means, a valve therein, and means for operating the same responsive to variation in the pressure of the compressible fluid within the tank whereby when a maximum fluid pressure has been reached within the tank the valve will divert the oil from the pump to the storage means, and a check valve in the line from the pump to the cushioning tank whereby fluid pressure will be held in the tank.

6. In a pumping apparatus of the type comprising an oscillating power actuated walking beam, cushioning and counterbalancing means comprising a cushioning cylinder pivoted at its lower end, a balancing cylinder rigidly associated with the cushioning cylinder, a piston within the balancing cylinder, a piston rod extending from said piston and pivotally connected to the walking beam, the portion of the balancing cylinder below the piston being filled with an incompressible fluid and a portion of the cushioning cylinder being filled with said incompressible fluid, a conduit establishing constant communication between the lower end of the balancing cylinder and the lower end of the cushioning cylinder whereby said incompressible fluid may have unrestricted flow between the two cylinders, the upper end of the cushioning

cylinder being filled with a compressible fluid, a second conduit establishing communication between the compression end of the balancing cylinder and the cushioning cylinder at a level below the level of the incompressible fluid in the cushioning cylinder and having a check valve therein opening toward the cushioning cylinder, a valve in the first named conduit between the balancing cylinder and the cushioning cylinder which when closed will cause the displaced fluid in the balancing cylinder to be forced directly into the cushioning cylinder through said second conduit, an air intake check valve in communication with the second named conduit whereby on the suction stroke of the piston within the balancing cylinder air will be drawn into the balancing cylinder and on the subsequent compression stroke of the balancing cylinder will be forced into the cushioning cylinder, a fluid inlet pipe communicating with the cushioning cylinder and within which a supply of incompressible fluid is maintained, a fluid storage tank, means for maintaining a constant flow of fluid from the storage tank to the cushioning cylinder through said fluid inlet pipe, and automatic means for interrupting said flow of fluid.

7. In a pumping apparatus of the type comprising an oscillating power actuated walking beam, cushioning and counterbalancing means comprising a cushioning cylinder pivoted at its lower end, a balancing cylinder rigidly associated with the cushioning cylinder, a piston within the balancing cylinder, a piston rod extending from said piston and pivotally connected to the walking beam, the portion of the balancing cylinder below the piston being filled with an incompressible fluid and a portion of the cushioning cylinder being filled

with said incompressible fluid, a conduit establishing constant communication between the lower end of the balancing cylinder and the lower end of the cushioning cylinder whereby said incompressible fluid may have unrestricted flow between the two cylinders, the upper end of the cushioning cylinder being filled with a compressible fluid, a second conduit establishing communication between the compression end of the balancing cylinder and the cushioning cylinder at a level below the level of the incompressible fluid in the cushioning cylinder and having a check valve therein opening toward the cushioning cylinder, a valve in the first named conduit between the balancing cylinder and the cushioning cylinder which when closed will cause the displaced fluid in the balancing cylinder to be forced directly into the cushioning cylinder through said second conduit, an air intake check valve in communication with the second named conduit whereby on the suction stroke of the piston within the balancing cylinder air will be drawn into the balancing cylinder and on the subsequent compression stroke of the balancing cylinder will be forced into the cushioning cylinder, a fluid inlet pipe communicating with the cushioning cylinder within which a supply of incompressible fluid is maintained, a fluid storage tank, means for maintaining a constant flow of fluid from the storage tank to the cushioning cylinder through said fluid inlet pipe, and means responsive to increase fluid pressure within the compression cylinder whereby the normal flow of fluid from the tank to the cushioning cylinder will be diverted into the tank.

CHARLES M. O'LEARY.
